CLAIM

The ornamental design for a sperm sampler, as shown and described.

DESCRIPTION

FIG. 1 is a front elevation view of a sperm sampler in accordance with one embodiment of the present invention.

FIG. 2 is a rear elevation view of the sperm sampler in accordance with one embodiment of the present invention.

FIG. 3 is a right elevation view of the sperm sampler in accordance with one embodiment of the present invention.

FIG. 4 is a left elevation view of the sperm sampler in accordance with one embodiment of the present invention.

FIG. 5 is a top plan view of the sperm sampler in accordance with one embodiment of the present invention.

FIG. 6 is a bottom plan view of the sperm sampler in accordance with one embodiment of the present invention.

FIG. 7 is a perspective view of the sperm sampler in accordance with one embodiment of the present invention.

FIG. 8 is a perspective view of the sperm sampler in accordance with one embodiment of the present invention.

FIG. 9 is a perspective view of the sperm sampler showing a base portion in broken lines separated from the device; and, FIG. 10 is a perspective view of the sperm sampler showing a base portion in broken lines attached to the device.

The broken line showing of parts of the drawings is included for the purpose of illustrating use and environment and forms no part of the claimed design.
